CLAIM

The ornamental design for a mattress cover, as shown and described.

DESCRIPTION

FIG. 1 is a top, front, and left side perspective view showing my new design.

FIGS. 2–4 are views of the mattress cover as it is shown in FIG. 1, wherein:

FIG. 2 is a bottom, back, and right side perspective view; FIG. 3 is a front view, the back view being identical thereof; and

FIG. 4 is a right side view, the left side view being identical thereof.

FIG. 5 is a top, front, and left side perspective view of a second embodiment of my new design.

FIGS. 6–8 are views of the mattress cover as it is shown in FIG. 5, wherein:

FIG. 6 is a bottom, back, and right side perspective view; FIG. 7 is a front view, the back view being identical thereof; and,

FIG. 8 is a left side view, the right side view being identical thereof.

The broken lines indicate portions of the mattress cover that form no part of the claimed design.
